Primary Examiner — Michael A. Pratt

(57) **CLAIM**

The ornamental design for a ventilation deflectors for car seats, as shown and described.

DESCRIPTION

FIG. 1 is a front, left and bottom perspective view of a first embodiment of a ventilation deflectors for car seats showing my new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view thereof shown in an environment of use;

FIG. 10 is a front, left and bottom perspective view of a second embodiment of a ventilation deflectors for car seats showing my new design;

FIG. 11 is a rear, right and top perspective view thereof;

FIG. 12 is a front view thereof;

FIG. 13 is a rear view thereof;

FIG. 14 is a left side view thereof;

FIG. 15 is a right side view thereof;

FIG. 16 is a top plan view thereof;

FIG. 17 is a bottom plan view thereof; and,

FIG. 18 is a perspective view thereof shown in an environment of use.

The even-length broken lines in the drawings illustrate portions of the ventilation deflectors for car seats that form no part of the claimed design. The uneven-length broken lines in the drawings are for the purpose of illustrating environmental subject matter that form no part of the claimed design.
